(57) **CLAIM**

The ornamental design for a window component extrusion, as shown and described.

DESCRIPTION

This application claims priority of the filing date of co-pending U.S. patent application Ser. No. 29/291,477 filed Aug. 30, 2007.

FIG. 1 is a top right perspective view of a window component extrusion.

FIG. 2 is a bottom left perspective view thereof.

FIG. 3 is top right perspective view of second embodiment of a window component extrusion.

FIG. 4 is bottom left perspective view thereof.

FIG. 5 is a top right perspective view of third embodiment of a window component extrusion.

FIG. 6 is a bottom left perspective view thereof.

FIG. 7 is a top right perspective view of a fourth embodiment of a window component extrusion; and,

FIG. 8 a bottom left perspective view thereof.

The claimed design is broken in the center indicating indefinite length.
